UNITED STATES PATENT OFFICE.

FRANK C. VIRTUE, OF TORONTO, ONTARIO, CANADA.

HAND-OPERATED AIR-PUMP.

1,025,221.

Specification of Letters Patent.

Patented May 7, 1912.

Application filed March 15, 1911. Serial No. 614,601.

To all whom it may concern:

Be it known that I, FRANK C. VIRTUE, of the city of Toronto, county of York, Province of Ontario, in the Dominion of Canada, have invented certain new and useful Improvements in Hand-Operated Air-Pumps; and I do hereby declare that the following is a full, clear, and exact description of the same.

10 The invention relates to improvements in hand operated air pumps as described in the following specification and illustrated in the accompanying drawings that form part of the same.

15 The invention consists essentially in the novel construction and arrangement of parts whereby a volume of air within a tubular casing is forced into an annular space surrounding a cylindrical plunger operating in said casing, by the inward movement of said plunger and is further compressed by the outward movement of said plunger and a further supply is coincidently drawn into said casing.

20 The object of the invention is to devise a hand operated pump by means of which air may be pumped into motor-car tires at sufficient pressure.

In the drawings Figure 1 is a perspective view of a pump constructed in accordance with this invention. Fig. 2 is an enlarged vertical sectional view of the pump broken intermediate of its length and showing the plunger in its innermost position. Fig. 3 25 is an enlarged vertical sectional view of the pump broken intermediate of its length and showing the plunger partly drawn out.

Like numerals of reference indicate corresponding parts in each figure.

30 Referring to the drawings, 1 is a tubular casing threaded externally at the ends and having a lug 2 projecting from its outer walls adjacent to the top, said lug having an air passage 3 therein communicating with the interior of the casing.

35 4 is a nipple threaded into the lug 2 at the outer end of the passage 3 and forming the connection for the flexible tube 5.

40 6 is the base of the pump threaded on to the lower threaded end of the casing 1 and having a lug 7 projecting laterally therefrom.

45 8 is the air inlet passage formed in the

base 6 and communicating with the interior of the casing 1 and extending out through the lug 7.

50 9 is a hollow ball headed plug threaded into the lug 7 at the outer end of the passage 8, the ball end 10 having the holes 11 in the side.

55 12 is a disk of leather or other suitable flexible material resting on the top surface of the base 6 and covering the inner end of the air passage 8 and having a hole 13 in the center thereof. The disk 12 forms a valve to close the air inlet passage and also forms a gasket against which the lower end of the casing 1 is screwed.

60 14 is a cap internally threaded and screwed to the upper threaded end of the casing 1, said cap having a central circular orifice 15 therethrough and an upwardly extending annular flange 16.

65 17 is a tubular plunger extending through the orifice 15 in the cap 14 and slidably engaging the flange 16.

70 18 is a circular plate sealing the lower end of the plunger 17 and projecting laterally beyond the outer wall thereof and having a central threaded stud 19 projecting downwardly therefrom.

75 20 is a cupped washer fitted over the plate 18 and having the upturned edge 21 extending between the projecting edge of the plate 18 and the inner wall of the casing 1.

80 22 is a plate secured on the stud 19 by the nut 23 and engaging the under side of the washer 20.

85 24 is a disk closing the upper end of the plunger 17 having a central threaded orifice 25 in which is secured the threaded shank of the handle 26.

90 27 is a cylindrical sleeve having its lower end 28 reduced to fit snugly around the plunger 17 and having a lateral flange 29 at its upper end. The flange 29 extends outwardly over the top end of the casing 1 and a gasket 30 encircling the sleeve 27 forms an air tight joint between the sleeve 27 and casing 1.

95 31 is a washer clamped between the top side of the flange 29 of the sleeve 27 and the inner side of the cap 14 and having its inner edge cupped inwardly between the sleeve 27 and plunger 17.

100 32 are foot plates hinged to the base 6

and are adapted to fold up neatly when the pump is not in use.

In the use of this device the tube 5 is first secured to the tire valve by a suitable coupling. The plunger 17 is then pulled upwardly by means of the handle 26 and a supply of air is drawn into the casing 1 through the air passage 8, the valve 12 lifting slightly to allow the ingress. The 10 downward movement of the plunger, compresses the air in the casing 1, forcing the valve 12 to close the inlet passage. As the compressed air cannot escape it is forced past the cupped washer 20 into the annular 15 space between the plunger 17 and casing 1, the pressure being held securely by the cupped washer 31. The air flows from the annular space within the casing through the passage 3 and tube 5 to the tire. The next 20 upward movement of the plunger further compresses the air in the annular space and forces it through the passage 3 into the tire against the pressure therein.

The area of the annular space is comparatively small, consequently the air may be forced at a very high pressure into the tire. The sleeve 27 holds the washer 31 in position and the reduced inner end engages the projecting portion of the plate 18 and forms 30 a positive stop to limit the upward move-

ment of the plunger 14 and to guard the washer 20 from injury.

What I claim as my invention is:

In a hand operated air pump, a tubular casing having an inlet air passage at the bottom, and an outlet passage adjacent to the top, a valve closing said inlet passage, a cylindrical plunger operating in said casing and forming an annular chamber therein, a cupped washer on the inner end of said 40 plunger, an annular cap closing the top of said casing and fitting snugly around said plunger, a cylindrical sleeve of larger internal diameter than the exterior of said plunger having a reduced inner end engaging 45 said plunger and an outwardly extending lateral flange at the outer end, a gasket arranged between said flange and the top of the casing, and a cupped washer having its inner edge cupped inwardly and extending 50 between the said cylindrical sleeve and said plunger.

Signed at the city of Toronto, county of York, Province of Ontario, Canada, this 2nd day of March 1911.

FRANK C. VIRTUE.
